UNITED STATES PATENT OFFICE

ROBERT G. MOIR, OF COQUITLAM, BRITISH COLUMBIA, CANADA

SHINGLE-CUTTING MACHINE

Application filed August 30, 1928. Serial No. 302,910.

This invention relates to a shingle cutting machine. Its principal object is to provide a machine which cuts a shingle with a knife instead of a saw as is usually done.

5 Resultant objectives emerging from my improved method of producing shingles are found in the complete elimination of sawdust, thus avoiding a serious proportion of wastage, carrying with it the obviation of the 10 necessity of apparatus for its removal both from the floor or from the neighboring atmosphere.

Other objects concerned are the reduction of fire risk and the surface improvement of 15 the shingle itself, which has a clean-cut surface instead of a rough one.

The means I adopt for securing these results may be stated broadly as consisting in the use of a revolving knife of special curved 20 form. This is mounted upon a disc having a slot therethrough it adjacent the curved cutting edge of the knife and through which the severed shingle passes when cut off the shingle block, the latter being fed up against 25 the revolving knife by suitable gear for this purpose.

The invention is better described by the aid of the drawings accompanying and forming a part of this application, in which:

30 Fig. 1 is a side elevation of the salient parts of a shingle cutter.

Fig. 2 is a front view.

Fig. 3 is a part sectional plan on line 3—3 of Fig. 4, and

35 Fig. 4 is a partial front view of the knife disc showing the relative positions of the knife and shingle block when the latter has been nearly cut through.

Fig. 1A is a view of the top feed roll ratchet 40 gear.

In these drawings similar numerals indicate identical parts in the several views, and the numeral 5 indicates the shingle block of cedar wood from which the shingles are cut by the curved knife 6. This latter is secured 45 to the heavy fly wheel disc 7 by the bolts 8 and has a special shaped concave cutting edge 9 so formed to obtain the required sliding contact of the knife edge with the wood block 5 and at the same time to maintain the general

direction of the cutting in line with the centre of the block 5 as indicated in Figs. 2 and 4.

The disc 7 is slotted adjacent the cutting edge of the knife 6 to a curved path 10, as shown in Fig. 4, and angularly as at 11 in Fig. 3, the purpose of which will be shown later.

The contiguous portions of the framework of the machine are indicated by 12. These carry the bearing 13 of the main spindle 14 and the lower feed rolls 15 which support and feed forward the shingle block 5. The top feed rolls 16 are not held in the framework but in the adjustable yoke 17 carried at each end by the levers 18 fulcrumed at 19 and held against the top of the block 5 by powerful 65 extension springs 20.

When the shingle block requires to be released from the grip of the feed rolls 15 and 16 the yoke 17 is raised against the tension of the springs 20 by the lever 21 fulcrumed at 22 70 and connected to a foot plate by the rod 23.

The feed rolls 15 and 16 are intermittently rotated by means of the cam-shaft 24 carrying the short and long throw cams 25 and 26. The short throw cam 25 engages the top friction roller 27 and the corresponding bottom friction roller 28 is engaged by the other cam 26. The rollers 27 and 28 are carried by the vertical rods 29 and 30 both of which latter receive vertical reciprocating motion in the guides 31 and 32 in alternate order as subsequently explained.

In order to maintain unity of operation in the cutting of the shingle block in view of the required wedge-shape section of the shingle, it is necessary to alternately tilt forward the top and bottom of the block 5 to produce the butt of the shingle alternately on its top and bottom edge.

This is effected by ratchet wheels 33 secured on the feed rolls 15 and 16 and rotated by ratchet lever 34 secured by spring catch 35 on the top roll and by ratchet lever 36 similarly connected to the bottom roll 15. The levers 34 and 36 are secured to and actuated by the rods 29 and 30, the latter rod 30 giving positive motion to the top roll 16 by a downward pull controlled by the cam 26 which compresses the spring 37 whilst the corresponding but opposite motion is given 90

to the rod 29 actuating the bottom roll 15 by an upward motion of the rod and the extension of the spring 38, the return motion being effected in each case by the oppositely acting springs 37 and 38.

5 In operating the machine the shingle block is inserted between the feed rolls 15 and 16 by depressing the lever 21 against the top spring 20 and raising the yoke 17 and the top feed 10 rolls 16.

15 The cutting disc 7 with the knife 6 attached is then rotated with the cam shaft 24, the cams 25 and 26 being timed to respectively force upwards and downwards the feed 20 rods 29 and 30, thus effecting a minimum and maximum feed to each feed roll in alternate order.

20 Having now particularly described my invention, what I claim and desire to be protected in by Letters Patent, is:

25 1. The combination with a shingle cutting machine, of a knife blade having its cutting edge revolvable in a plane substantially right-angular to the centre of the shingle 30 block, the cutting edge of said blade forming a curve on the plane of its revolution of approximately spiral character, means in connection with the driving gear of said machine whereby the surface of a shingle 35 block is intermittently presented to the plane of operation of said knife at an alternate angular inclination whilst the top and bottom edges of said block are maintained in parallelism with said plane.

40 2. The combination with a shingle cutting machine, of a knife blade having its cutting edge revolvable in a plane substantially right-angular to the centre of the shingle 45 block, the cutting edge of said blade forming a curve on the plane of its revolution of approximately spiral character, feed rolls on the upper and under sides of said shingle block carrying ratchet wheels, ratchet levers 50 secured to said levers and slidable in guides on the framework of said machine, an extension spring and a compression spring respectively engaging each said rod whereby the return strokes of the said rods are made 55 in opposite directions, a cam shaft operating cams adapted to impart to each of the said vertical rods a short and a long stroke in alternate order whereby the top and bottom edges of the shingle block which are parallel 60 to the plane of the cut of the revolvable knife are alternately tilted forward towards the 65 said plane.

In testimony whereof I affix my signature.
ROBERT G. MOIR.
